UNITED STATES PATENT OFFICE.

KARL JOSEPH SECK, OF MAINZ, GERMANY.

MECHANICALLY-OPERATED BOAT.

No. 904,154.

Specification of Letters Patent.

Patented Nov. 17, 1908.

Application filed November 3, 1905. Serial No. 285,791.

To all whom it may concern:

Be it known that I, KARL JOSEPH SECK, mechanician, residing at Mainz, No. 3 Gymnasium street, in the Grand Duchy of Hesse, Germany, have invented new and useful Improvements in Mechanically-Operated Boats, of which the following is a specification.

My invention relates to boats which are propelled by paddles, operated by a series of mechanism from a common bar or bars actuated by manual or motor power, and by setting this bar, the course of the boat may be directed straight ahead, or backward, side-wise to right or left, around its vertical axis, or around a point in its longitudinal axis, and may be used for pleasure or other purposes.

The advantages of my improved boat over others are, its easy management, the power necessary to propel the boat is reduced to a minimum, that it can be used without a rudder and that under the most trying conditions it can not capsize.

My improved boat consists as it may happen of two boats secured together by bridge pieces, or of only one boat carrying the propelling mechanism, comprising one or more sets of paddles operated by chain- or sprocket-wheels from sprocket-wheels at the center of the boat, a disk adjustably fastened to said center wheels, a hand-bar adjustably secured to said disk, and means for controlling the individual paddles to bring and maintain them in the direction, which is at right angles to the stroke.

My invention further consists of improvements hereinafter more fully described and pointed out in the claims.

My invention will be more fully understood taken in connection with the accompanying drawings forming part hereof, and in which:

Figure 1, is a top view of my improved boat, showing the twin-boats bridged together, the paddle mechanism, the operating sprocket-wheels, disk and hand-bar, also a rudder with means for operating the same, and anchor with hoisting device. Fig. 2, is a longitudinal section on the line 2—2 of Fig. 1. Fig. 3 is a cross-section on the line 3—3 of Fig. 1. Fig. 4 is a top-view of the paddle operating mechanism, with the hand-bar. Fig. 5, is a central section of the operating mechanism shown in Fig. 4. Fig. 6, is an elevation of the paddles arranged in pairs, and supported from the bridge pieces

by means of a stud and a cross-bar. Fig. 7, is a top-view of the paddles, their supporting bar and the mechanism for maintaining the individual paddles in normal actuating position. Fig. 8, is a section showing the mounting of a paddle upon its supporting bar, and Fig. 9, is a section showing the stud and paddle-supporting bar on the line 9—9 of Fig. 8.

Referring now to the drawings for a further description of my invention, *a* and *a* are the twin-boats coupled together by means of the distance- or bridge-pieces *d*, the distance at the fore-end between the twin-boats is smaller than at the rear in order to reduce the resistance of the water acting on the sides of the twin-boats, when the boat is being propelled. Each of the twin-boats is provided with recesses *c*, which may be closed by lids *b*, and these recesses are provided with foot rests for the crew; other arrangements for the seating of the crew and other persons may of course be made.

On top of the distance or bridge pieces *d*, is secured a plank *e*, on which all the operating mechanism for the boat is mounted. To propel the boat, paddles *f* operating only in one direction, are provided, and are actuated and controlled as hereinafter more fully described. These paddles *f* are mounted at the ends of a paddle-bar *g* of which one or more may be arranged and pivoted in the longitudinal axis of the boat in the plank *e*, in the drawings, four of such bars *g* with two paddles *f* each are shown. These paddle-bars *g* are mounted on short shafts *h*, Figs. 6, 7 and 8, in any preferred manner and are oscillated about their centers by chain- or sprocket-wheels *i* secured to said shafts *h*.

An oscillating motion is imparted to these shafts *h* from the sprocket-wheels *j*, *k* mounted loosely on the stud *l* at the center of the plank *e*. Mounted loosely on the same stud *l* and above the sprocket-wheels *j*, *k* is a disk *m* having a rim *n* with series of notches *o*, for a purpose to be presently described. Above the disk is further mounted loosely on the stud *l* a hand-bar *p* having lugs to engage one of the said series of notches *o*, and to keep the lugs engaged in said notches, a spring is employed in a well known manner. Normally the sprocket-wheels *j*, *k*, and disk *m* are held together or in operative position by means of a removable pin *q* engaging the distance blocks *r* between the wheels *j*, *k* and disk *m*, and when the hand-bar *p* is oscillated

the two or more paddle-bars *g* move in unison therewith.

The middle part of the hand-bar is partly cut away, in order to display the word indicating the direction in which the boat is to be propelled. In Fig. 4, the hand-bar *p* is set on "Forward", and both paddle-bars with paddles are operated to propel the boat in that direction. If the disk *m* with the sprocket-wheels *j*, *k* still coupled together by the pin are rotated 30 degrees and the lugs on the hand-bar engage the notches *o* the slot in the hand-bar displaying "To right", then the proportion of the diameter of the chain wheels *i* to that of the chain wheels *j*, *k*, being as 1 to 3 the paddle-bars *g* assume the normal direction in line with the longitudinal axis of the boat, and the latter will be propelled or pushed to the right. A similar result will be obtained but the direction of the boat is changed to left, if the hand-bar *p* is set at "To left" that is to say, turned 90° from the "Forward" position, and the bar *p* may be set in any notches between those just mentioned, to propel the boat at any angle desired. To propel the boat backward, the paddle-bars *g* are turned 180 degrees, by turning the disk *m* and wheels *j*, *k* 180 degrees. To propel or swing the boat about its center, or a vertical axis through the stud *h* the coupling pin *q* is lifted and the lower wheel *k* is turned by means of a lever *s* engaging the lower wheel *k*, the pin *q* engaging the hole 26 in the wheel *k* this brings the paddle-bars again in line with the longitudinal axis of the boat, but the paddles work in opposite direction, as will be more fully described. The boat may be rotated toward the right or left in this manner, according to whether the wheel *k* is turned either toward the right or left. To propel the boat about the center, for instance of the rear paddle-bar *g*, and with the front of boat toward the left, the wheel *k* is entirely uncoupled and the wheel *j* with disk *m* is coupled to the hand-bar *p* so as to display "To left".

At the ends of the paddle-bars *g* are secured sleeves or journal-boxes *t*, in which stems *u* are rotatably mounted, Figs. 7, 8 and 9, the paddles *f* are provided with hinge-straps *v* and mounted on the trunnions *w* secured to the said stems *u*. To hold the paddle *f* in operative or active position, the paddle is provided with a slanting offset *x* corresponding with the beveled lower end of the said stem, Fig. 9, so that the paddle when moved against the water, will be in vertical position and when moved away from the water, it will float over or with the same.

To keep the paddle when in action in the proper direction or what may be called the efficient position, that is at 90 degrees to the direction in which the boat is to be propelled,

the short shaft *h* of the paddle-bar *g* is provided with a cross bar *y*, and this bar is held by the helical spring *z* normally in line with the longitudinal axis of the boat.

The stems *u* are provided with arms 10, 70 as shown in Figs. 7 and 9, extending on opposite sides of a paddle-bar *g* and the ends of these arms 10 are connected to the respective ends of the bar *y* by means of connecting rods 11 so that when the paddle-bars *g* are 75 oscillated, the paddles *f* maintain an efficient position in relation to the water, which is at 90 degrees to the course of the boat.

The cross-bar *y* is provided with notches 12 and the paddle-bar *g* with studs 13 to 80 limit the oscillatory movement of the paddle-bar when in rowing action. When however the paddle-bar *g* is reversed 180 degrees the wedge-shaped ends of the studs 13 and the spring *z* will allow the cross-bar *y* to pass 85 over the studs 13.

The boat may also be provided with an anchor 14 and if such is employed it may be operated from the handle-bar *p* and the sprocket wheels *i* and *k*, in such case the 90 shaft *h* is provided with another sprocket-wheel 15, driving a wheel 16, ratchet-wheel 17 and winding-drum 18 for the anchor-chain, which are all secured to one shaft journaled in the end of the plank *e*. A pawl 95 19 engaging the ratchet-wheel 17 is pivoted to the plank *e* and caused to engage with the ratchet-wheel 17 by a spring. The sprocket-wheels *i* and 15 may be coupled together by a pin, when the anchor 14 is to be raised, the 100 boat moving in such instance toward the anchor.

Having thus described the nature and objects of my invention, what I claim as new and desire to secure by Letters Patent is: 105

1. A boat composed of twin-boats coupled together by bridge-pieces, a plank in the center midway between the twin-boats, one or more paddle-bars rotatably mounted on said plank, a hand-bar pivoted at the center of the boats to the said plank, means for connecting said hand-bar with said paddle-bars, paddles trunnioned to the ends of the paddle-bars and back-stops for said paddles, substantially as and for the purpose set forth. 115

2. A boat composed of twin-boats coupled together by bridge-pieces, a plank in the center midway between the twin-boats, one or more paddle-bars rotatably mounted on said plank, a stud secured in the center of the said 120 plank, a sprocket-wheel for each paddle-bar mounted on said stud a notched disk on the stud, a hand-bar also mounted on said stud and engaging the said notches of the disk, means for coupling the said sprocket-wheels to said disk and means for transmitting motion from the hand-bars to said paddle-bars, substantially as and for the purpose set forth. 125

3. A boat composed of twin-boats coupled together by bridge-pieces, a plank in the cen- 130

- ter midway between the twin-boats, one or more paddle-bars rotatably mounted on said plank, a stud provided at the center of the boat in the plank, a sprocket-wheel for each 5 paddle-bar mounted on said stud, a disk provided with a rim and notches, mounted on said stud, a hand-bar fitting over said stud and adapted to engage certain of said notches, a coupling-pin between the sprocket-wheels and 10 the said disk, means to impart motion from the sprocket wheels to the said paddle-bars, a paddle on each end of said paddle-bars, a back-stop for each paddle, and means for maintaining the paddles in operative position 15 while the paddle-bars are oscillated, substantially as and for the purposes set forth.
4. A boat composed of twin-boats coupled together as described, a pivoted hand-bar, paddle-bars and paddles, means for operating 20 said paddle-bars, in combination with an anchor, means for raising said anchor and connection between said hand-bar and said means for raising said anchor, substantially as and for the purpose set forth.
- 25 5. A propelling mechanism for boats, comprising a paddle-carrying arm mounted to turn about a vertical axis, an oscillating

member operatively connected with said arm, and an operating member normally held to turn with the oscillating member, but adjustable about the center thereof. 30

6. A propelling mechanism for boats, comprising a paddle-carrying arm mounted to turn about a vertical axis, an oscillating sprocket - wheel, a chain connecting said 35 sprocket-wheel with the arm, and an oscillating operating member adjustably connected with said sprocket-wheel.

7. A propelling mechanism for boats, comprising an oscillating operating member located at the central portion of the boat, two oscillating members adjacent to said operating member, means whereby one or both oscillating members may be connected with the operating member, and paddle-carrying bars 40 45 located in front and in rear of the operating member and connected with the respective oscillating members.

In testimony whereof I affix my signature in presence of two witnesses.
